(57) **CLAIM**

The ornamental design for a calf bottle, as shown and described.

DESCRIPTION

The design is for a bottle which is particularly useful for feeding calves.

FIG. 1 is a top plan view of a first embodiment of the calf bottle of the claimed design;

FIG. 2 is a bottom plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top, rear, and right side perspective view thereof;

FIG. 8 is a top, rear, and left side perspective view thereof, shown in an inverted position;

FIG. 9 is a top plan view of a second embodiment of the calf bottle of the claimed design;

FIG. 10 is a bottom plan view thereof;

FIG. 11 is a front elevational view thereof;

FIG. 12 is a left side elevational view thereof;

FIG. 13 is a right side elevational view thereof;

FIG. 14 is a rear elevational view thereof;

FIG. 15 is a top, rear, and left side perspective view thereof; and,

FIG. 16 is a top, rear, and right side perspective view thereof, shown in an inverted position.
